UNITED STATES PATENT OFFICE

164,933

DRIPLESS PITCHER

Robert H. Killebrew, Des Moines, Iowa

Application October 12, 1950, Serial No. 12,534

Term of patent 14 years

(Cl. D44—21)

To all whom it may concern:

Be it known that I, Robert H. Killebrew, a citizen of the United States, residing at Des Moines, in the county of Polk and State of Iowa, have invented a new, original, and ornamental Design for a Dripless Pitcher, of which the following is a specification, reference being had to the accompanying drawing, forming a part thereof.

Fig. 1 is a perspective view of a dripless pitcher, showing my new design;

Fig. 2 is a top plan view; and

Fig. 3 is a side elevational view thereof. The opposite side is similar to the side shown.

I claim:

The ornamental design for a dripless pitcher, substantially as shown and described.

ROBERT H. KILLEBREW.
